UNITED STATES PATENT OFFICE.

JOHN T. QUINN, OF LOS ANGELES, CALIFORNIA, ASSIGNOR TO JOHN BRIGHTCLIFFE, OF SAME PLACE.

DESIGN FOR A TOY.

SPECIFICATION forming part of Design No. 27,044, dated May 11, 1897.

Application filed March 10, 1897. Serial No. 626,886. Term of patent 14 years.

To all whom it may concern.

Be it known that I, JOHN T. QUINN, a citizen of the United States, residing at Los Angeles, in the county of Los Angeles and State 5 of California, have invented a new and original Design for a Toy, of which the following is a specification.

This invention relates to a new and original design for a toy; and it has for its object to 10 provide a design of this character that shall be both useful and ornamental.

The leading feature of the design resides in a toy having a flat body of an approximate triangular form and provided with a plurality 15 of radially-extending regularly-spaced V-shaped arms and a convexed disk-like figure arranged at the vertex of each V-shaped arm and joined thereto.

A minor feature of the design resides in 20 the flat body of the toy having a central circular portion, from which the V-shaped arms radiate, and in the central circular portion of the body and the disk-like figures, having circular openings.

25 In the drawings, Figure 1 is a perspective

view of a toy embodying the herein-described design. Fig. 2 is a plan view thereof.

Referring to the accompanying drawings, the numeral 1 designates a flat body of an approximate triangular form and having a central circular portion 2, provided with a pair of centrally-located circular openings 3. The flat body 1 is further provided with a plurality of regularly-spaced V-shaped arms 4, extending radially from the central circular portion 2, and at the vertex of each V-shaped arm 4 is arranged a convexed disk-like figure 5. The disk-like figures 5 are joined to the vertices of the arms 4 and are provided at their centers with circular openings 6.

What I claim is—

The design for a toy herein shown and described.

In testimony that I claim the foregoing as my own I have hereto affixed my signature in 45 the presence of two witnesses.

JOHN T. QUINN.

Witnesses:

JOHN BRIGHTCLIFFE,
JOHN McCONNACHIE.
